UNITED STATES PATENT OFFICE.

EDWARD H. ZELLER, OF CLEVELAND, OHIO.

EYEGLASS-FASTENER.

No. 848,715.

Specification of Letters Patent.

Patented April 2, 1907.

Application filed July 30, 1906. Serial No. 328,418.

To all whom it may concern:

Be it known that I, EDWARD H. ZELLER, a citizen of the United States, residing at Cleveland, in the county of Cuyahoga and State of Ohio, have invented certain new and useful Improvements in Eyeglass-Fasteners; and I do declare the following to be a full, clear, and exact description of the invention, such as will enable others skilled in the art to which it appertains to make and use the same.

My invention is an improved eyeglass-fastener for mounting the rimless lenses of an eyeglass; and it consists in a lens having rabbets in opposite sides thereof to provide outwardly-diverging surfaces, and a fastening element having a fork astride of said rabbeted portions of the lens and with its arms in engagement with said outwardly-diverging surfaces of said rabbets to effect a dovetail engagement between said fastening element and said lens, as hereinafter described and claimed.

In the accompanying drawings, Figure 1 is an elevation of an eyeglass-lens and a fastening element constructed in accordance with my invention. Fig. 2 is a similar view at right angles to Fig. 1. Fig. 3 is a detail-elevation of the lens. Fig. 4 is a sectional view through the lens and the fastening element, taken on the plane indicated by the line *a a* of Fig. 1; and Fig. 5 is a detail perspective view of the fastening element.

The lens 1 is, in accordance with my invention, provided at one end with substantially quarter-circular rabbets 2, the bottoms of which form outwardly-diverging surfaces 3. For the purposes of this specification the said rabbets are here shown as of considerable depth. In practice they will be very shallow and will be hardly perceptible except upon a close examination. The eyeglass-fastening element 4, which may be a portion of the bridge-piece or of the eyelet to which the chain or guard is attached, is provided at the end with a broadened head 5 to bear against the edge of the lens, and the said head is bifurcated to form a fork, the arms 6 of which are pressed into engagement with the

bottoms of the rabbets 2, so that a dovetail or double-wedge connection is formed between the lens and the fastening element, as shown.

It will be understood that by means of my improved construction of the lens and of the fastening element the lens is not weakened by a givet or screw hole therein, as in the usual construction, and it will be also understood that the fastening element is securely attached to a lens and can only be casually separated therefrom either by striking the lens or by exerting such tension on the fastening element as to cause the eyelet 6 or its forked head to open. It will also be understood that by reason of the engagement of the broadened forked head with the edge of the lens there will be no pivotal movement between the lens and the fastening element.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of the invention as defined by the appended claim.

Having thus described my invention, what I claim as new, and desire to secure by Letters Patent, is—

A lens rabbeted in opposite sides near one edge to provide outwardly-diverging surfaces, in combination with a fastening element having a fork to engage one edge of the lens and fork-arms to engage such surfaces thereof to effect a dovetail connection between said lens and said fastening element, substantially as described.

In testimony whereof I have hereunto set my hand in presence of two subscribing witnesses.

EDWARD H. ZELLER.
